UNITED STATES PATENT OFFICE.

WILLIAM W. DUNN, OF MALDEN, MASSACHUSETTS, ASSIGNOR TO SILEX COMPANY, OF MALDEN, MASSACHUSETTS, A CORPORATION OF CONNECTICUT.

DESIGN FOR A HANDLE FOR PERCOLATORS.

Application filed March 19, 1925. Serial No. 12,773. Term of patent 7 years.

To all whom it may concern:

Be it known that I, WILLIAM W. DUNN, a citizen of the United States of America, residing at Malden, in the county of Middlesex and State of Massachusetts, have invented a new, original, and ornamental Design for Handle for Percolators, of which the following is a specification, reference being had to the accompanying drawings, forming part thereof.

Referring to the drawings,

Fig. 1 is a top plan view of a handle for percolators showing my new design.

Fig. 2 is a front view of the same.

I claim,

The ornamental design for a handle for percolators, as shown.

In witness whereof I hereunto subscribe my name this 7th day of March, A. D. 1925.

WILLIAM W. DUNN.
